CONVEYER SYSTEM

Chester S. Jennings, Syracuse, N. Y., assignor to
 The Lamson Company, Syracuse, N. Y., a corporation of Massachusetts

Application December 29, 1933, Serial No. 704,448

9 Claims. (Cl. 198—138)

This invention relates to a conveyer system and more particularly to a system wherein the load supporting elements keep the loads in planes parallel to a selected plane, usually horizontal, while the loads are transported.

5 The primary object of this invention is to provide a conveyer system which comprises an endless chain or similar elements, a plurality of load supporting cars carried by the chain, mechanism for guiding the cars around corners from one plane of travel to another and means for maintaining them with their load supporting surfaces at all times in planes parallel to a selected plane usually horizontal.

10 15 A further object of this invention is to provide, in a conveyer of the type above mentioned wherein each car is fixed at one end only to the chains, the other end being free, supplementary means for engaging the free ends of the cars during their upward and downward travel and moving them positively in unison with the fixed ends of the cars; such supplementary means being in the embodiment hereinafter described, of two types, to wit; intermediate sprockets driven 20 in unison with the chain sprockets and auxiliary chains traveling in unison with the main chain.

25 30 Another object of this invention is to provide means for steadyng the cars in case any tipping takes place while passing around the corners of the conveyer.

35 Other objects will appear from a consideration of the following description of one embodiment of this invention adapted for use in a shoe factory and of the illustration of such embodiment in the accompanying drawings wherein:—

Fig. 1 is a view in side elevation of a conveyer system embodying this invention;

Figs. 2 and 3 are enlarged elevation views of two of the riser units in such system;

40 Fig. 4 is a cross sectional view taken along the line 4—4 in Fig. 2 on a somewhat larger scale;

Fig. 5 is an enlarged elevation view of one end of such system;

Fig. 6 is a plan view of such end;

45 Figs. 7 and 8 are respectively side elevation and plan views of a portion of an auxiliary chain;

Fig. 9 is a side elevation view of the end sprockets for an auxiliary chain;

50 Fig. 10 is a similar view of an intermediate sprocket;

Figs. 11 and 12 illustrate a holding guide in front and side elevations respectively; and

55 Figs. 13, 14 and 15 illustrate a typical rack car for the system shown in Fig. 1, Fig. 13 being a

plan view of a portion of the car, Fig. 14 being a front elevation thereof and Fig. 15 being a cross sectional view taken along the line 15—15 of Fig. 14.

Fig. 1 of the drawings illustrates a typical installation embodying this invention wherein cars 20 travel in both horizontal and vertical planes while the load transporting surfaces thereof remain at all times level, i. e. as here shown horizontal. The cars are secured to an endless chain 21 and travel in tracks defined along the horizontal stretches by rails 22 and along the vertical stretches by rails 23 and 24. The direction of travel of the cars in the installation shown in Fig. 1 is indicated by arrows placed thereon, the cars moving upward through the riser units 25 and downward through the riser units 26. The chain 21 travels around end sprockets 27 one at least of which is driven in the usual way and is guided through the riser units 25 and 26 by sprockets 28.

5 10 15 20 25 30 35 40 45 50 55 As will be pointed out below the direction of travel may be reversed when desired. In the selected illustration the cars are raised from and then returned to a definite level to carry them over an aisle or over some obstacle but obviously the vertical travel might be for other purposes such as for instance to raise or lower the cars from one floor or level to another. Furthermore the upward and downward paths of travel, although shown and described as vertical might be inclined or curved should necessity arise and it will be understood that the reference herein to vertical paths includes any paths along which the cars might be raised or lowered.

The installation shown in Fig. 1 is for the purpose of handling shoes in a shoe factory and the cars 20 (Figs. 13, 14 and 15) are of the shoe rack type shown and described in the copending application of Perry and Jennings, Serial No. 686,814, filed August 25, 1933. Each car 20 comprises a support 30 and paddles 31 removably secured to the support and on which rest the shoes being carried. Fixed to the back of the support 30 adjacent each end are a pair of spaced wear plates 32 mounted upon a sleeve 33 and a freely rotatable wheel 34 mounted between each pair of plates 32. As shown in Fig. 15 the wheel 34 rides on the edges of the rails which define the tracks and is held thereon by the wear plates 32 which extend over both sides of the rails. The car is fixed at one end to the chain 21 by a pin 35 which passes through the sleeve 33 at that end while the other end of the car is free from the chain. A stud 36 fixed in the sleeve 33 at the other end of the car terminates short of the

chain. Formed in the support 30 near the ends thereof are pairs of pockets 37, the pair near the free end of the car carrying car cams 38 and the pair near the fixed end of the car carrying 5 positioning plates 39. The cam 38 and plate 39 are identical at the inner ends and may be inserted in any pocket 37 their location merely depending upon which end of the car is fixed directly to the chain and differ from each other 10 only by the provision at the outer end of the cam 38 of a nose 40 which completes a recess 41.

Each riser comprises a frame provided with a main track, defined by the rails 23 and 24, behind which the chain 21 travels and a supplementary 15 track defined by the rails 50 and 51. An auxiliary chain 52 passes around end sprockets 53 and one run thereof travels behind the supplementary track in the same direction and at the same rate of speed as the main chain travels 20 behind the main track. The sprocket 28 and one of the sprockets 53 are positively driven in unison by any suitable means such as a spur gear which meshes with gears (not shown) fixed to the sprocket shafts. The chain 52 (see Figs. 7 and 8) comprises alternately arranged links 56 and 57, the former being a bar having a curved inner edge, the latter being two plates secured at either side of the bar. A recess 58 is formed in each link at the outer face of the chain. The 30 sprockets 53 (see Fig. 9) have at their periphery a plurality of arcuate depressions 59 in which the links 56 rest and intermediate portions 60 which extend between the plates of the links 57 and bear upon the ends of the link bars 56. Between the 35 sprockets 53 are mounted guide rails 63 against which the inner faces of the links 56 rest and past which both sides of the plates of the links 57 extend.

Mounted in the frame of each riser unit between and in alignment with sprockets 28 and 53 is a notched sprocket 65 driven from the sprocket 28 by a spur gear 66 which meshes with gears mounted upon the shafts of the sprockets 28 and 65. The sprocket 65 has arcuate depressions 59 like the sprocket 53, and teeth 61 which separate the depressions and are provided with notches 62 which register with recesses 58 in the link plates 57 and are adapted to receive the studs 36 of the cars. Associated with each of the end 50 sprockets 27 over which the chain 21 travels is a notched intermediate sprocket 70 which is driven in unison therefrom through a gear assembly 71 or similar mechanism and which engages the stud 36 on each car and thus moves 55 the free end of the car in unison with the fixed end as the latter is carried by the chain around the end sprocket. In the illustrated installation each sprocket 70 is at the right of a sprocket 27. A face plate 72 fixed to the frame in front 60 of the sprocket 27 coacts with the studs to insure their location in the notches of the sprockets 70. Behind the sprockets 70 at the left hand end of the installation and in alignment with the sprocket 27 is mounted a bar 73 on which the 65 chain 21 rests and by which the fixed end of the car is held against shifting. The rotation of the sprockets 65 and 70 is so timed that the stud of each car will enter one of the notches therein. It will be understood that each of the 70 sprockets 65 and 70 coacts with the adjacent chain sprocket to move the free end of a car in unison with the fixed end thereof which is carried by the chain around that sprocket.

Projecting from the frame adjacent each of the 75 corners thereof are guides 75 and 76. The guide

75 which is curved and the guide 76 which is straight coacts with the car cams 38 to direct the travel of the free ends of the cars as will be pointed out below. Guides 75 alone are provided at the bottom of both right hand units, guides 76 alone are provided at the top of such units, at the bottom of both left hand units, and at the top and bottom of the sprocket 27 and wheel 70 assembly at the right end of the installation, and both guides 75 and 76 are provided at the top 10 of the left hand units and at the top and bottom of the sprocket 27 and wheel 70 assembly at the left end of the installation. At each of the corners of the installation are mounted on the frame holding guides 77 having tongues 78 spaced from 15 and parallel to the face of the frame for purposes hereinafter described.

The operation of the illustrated installation will be described in connection with the travel of a car 20 starting at the left end of Fig. 1 20 and traveling in accordance with the arrows applied thereon. It will be understood that at the start the forward end of the car is free and that the rearward end is fixed to the chain. The car travels through the path defined by the guides 22, the free end passing below the sprockets 28 and 65 of the riser unit 25. The guide 76 enters the recess 41 in the car cam 38 to prevent the free end of the car from entering the main track of the riser. As the fixed end is carried by the chain 21 around the sprocket 28 into the main path defined by the rails 23 and 24 the notch in one tooth of the sprocket 65 receives the stud 36 of the car and raises the free end of the car into the supplementary path defined by the rails 50 and 51. The upward movements of both ends of the cars take place simultaneously. As the free end of the car is raised by the sprocket 65 the plates of one of the links 57 of the auxiliary chain 52 pass at opposite sides of the teeth of the sprocket 65 and receive the stud 36 of the car in one of the recesses 58. The upward movement of the free end of the car is thus continued in unison with that of the fixed end. When the car reaches the top of the riser unit 40 25 the cam 38 at the free end passes upwardly into contact with the curved guide 75 and is directed thereby to the straight guide 76 which obviously enters the recess 41 below the nose 40 of the guide. The free end of the car is thus held in the horizontal path and prevented from following the auxiliary chain 52 downwardly. The car is then moved by the chain 21 to the top of the unit 26 and as it reaches this unit the cam 38 engages the guide 76 and prevents the 55 car from entering the main track of the riser. The ends of the car are caused to travel in unison down the main and supplementary tracks of the riser unit by the chain 21 and the auxiliary chain 52 in the manner previously described 60 so that the car remains horizontal. In making the turn at the right hand end of the installation the cam 38 engages the guide 76 so that the free end of the car is prevented from entering the main track and passes around the wheel 70. 65 Thereafter the car proceeds with the free end in the rear. The guide 75 at the bottom of the riser 25 engages the cam 38 and directs the free end of the car to the sprocket 65. The upward travel of the car is the same as that already described in connection with the left hand unit 25. Upon arriving at the top of the unit the car is then moved horizontally to the left hand riser unit 26, the guide 76 at the top of the unit 25 preventing the free end of the car from dropping 70 75

info the main track of the riser unit. As the car arrives at the top of the unit 26, the guides 75 and 76 coat to direct the free end of the car into engagement with the auxiliary chain 52. The car 5 thus descends through the unit while remaining horizontal, is advanced by the chain to the left hand end of the installation directed by the guides 75 and 76 around the sprocket 70 and returns to the starting point. If desired the chain 10 may be driven in the opposite direction and the car will pass through the risers while in a level or horizontal position. This will be apparent from an examination of the drawings and will not be set forth herein.

15 It will be understood in this description of the car travel that the positioning plates 39 are so formed that they will normally pass the guides 75 and 76 without contacting therewith. In order to prevent such contact due to a tilting on account of vibration or the like the holding guides 77 are provided which in case of any tipping, engage the plates 39 thus steadyng the car and preventing the plates 39 from contacting with the guides 75 and 76 at the corners of the installation.

23. Station. While one embodiment of this invention is adapted for the transportation of shoes in a shoe factory it will be understood that I am not limited thereto and that other embodiments 30 of the invention and other uses thereof may be made without departing from the spirit and scope of this invention as set forth in the following claims.

I claim:

35 1. A conveyor system wherein load supporting cars travel along horizontal, upward and downward paths, comprising an endless main chain, sprockets, over which said chain passes located at the corners of the system where the cars
40 change their direction of travel, a plurality of cars each fixed to said chain adjacent one end, the other end being free, a stud adjacent the free end of each car, and means adjacent said sprockets and driven in unison therewith to engage the studs of the cars and maintaining the cars, as they travel around said corners and during their upward and downward travel, in planes parallel to those in which they travel horizontally, said means including an auxiliary chain
45 50 having links each consisting of two bars with notches in the outer face of the link, in which notches the studs of the cars are received during the upward and downward travel thereof.

2. A conveyer system wherein load supporting cars travel along horizontal, upward and downward paths, comprising an endless main chain, sprockets, over which said chain passes located at the corners of the system where the cars change their direction of travel, a plurality of cars each fixed to said chain adjacent one end, the other end being free, a stud adjacent the free end of each car, and means adjacent said sprockets and driven in unison therewith to engage the studs of the cars and maintaining the cars, as they travel around said corners and during their upward and downward travel, in planes parallel to those in which they travel horizontally, said means including an auxilliary chain having links each consisting of two bars with notches in the outer face of the link, one run of which auxiliary chain travels parallel to and in the same direction as the main chain and removably receives in the notches of the links the studs of the cars during the upward and downward movement thereof.

3. A conveyer system wherein load supporting cars travel along horizontal upward and downward paths, comprising an endless main chain, sprockets, over which said chain passes, located at the corners of the system where the cars change their direction of travel, a plurality of cars each fixed to said chain adjacent one end, the other end being free, a stud adjacent the free end of each car, and means adjacent said sprockets and driven in unison therewith to engage the studs of the cars and maintaining the cars, as they travel around said corners and during their upward and downward travel, in planes parallel to those in which they travel horizontally, said means including a sprocket having spaced depressions therein in which depressions the studs of the cars are received and the free ends moved in unison with the movement of the fixed ends by the main chain as it passes around the adjacent corner sprocket and auxiliary chain to which the studs of the cars pass from the sprocket so that both ends of the cars are raised in unison by the main and auxiliary chains. 5 10 15 20

4. In a conveyer system wherein cars fixed at one end to a main chain are transported, a riser unit comprising a frame, rails secured thereto and defining a main track behind which the main chain travels and a supplementary track parallel to the main track, an auxiliary chain one run of which travels behind the supplementary track said auxiliary chain being adapted to engage the free ends of the cars and coacting with the main chain to move said cars through the riser unit, and means for raising the free end of the car into engagement with the auxiliary chain.

5. In a conveyer system wherein cars fixed at one end to a main chain are transported, a riser unit comprising a frame, rails secured thereto and defining a main track behind which the main chain travels and a supplementary track parallel to the main track, a sprocket around which the main chain passes into the riser unit, an auxiliary chain, one run of which travels behind the supplementary track said auxiliary chain being adapted to engage the free ends of the cars and coacting with the main chain to move said cars through the riser, and an intermediate sprocket which engages the free end of the car and raises it in engagement with the auxiliary chain. 40 45 50

6. In a conveyer system wherein cars fixed at one end to a main chain are transported, a riser unit comprising a frame, rails secured thereto and defining a main track behind which the main chain travels and a supplementary track parallel to the main track, a sprocket around which the main chain passes into the riser unit, an auxiliary chain, one run of which travels behind the supplementary track said auxiliary chain being adapted to engage the free ends of the cars and coacting with the main chain to move said cars through the riser, an intermediate sprocket which engages the free end of the car and raises it in engagement with the auxiliary chain, and means for driving said intermediate sprocket in unison with said main chain sprocket. 55 60 65

7. In a conveyer system wherein cars fixed at one end to a main chain and having projecting studs at the free ends, are transported by the main chain through a track having horizontal lengths and corners therein, said cars having car cams at the free ends and positioning plates at the fixed ends, sprockets with which said chain engages at the corners of the tracks, intermediate sprockets driven by said chain sprockets and hav- 75

- ing notches which receive the studs at the free ends of the cars, guides adjacent the corners with which the cams at the free ends of the cars engage to direct the free ends of the cars toward 5 the intermediate sprockets, the positioning plates normally passing freely over the guides, and holding guides which, in case the cars tip, engage the positioning plates and prevent them from contacting with the guides.
- 10 8. In a conveyer system wherein cars fixed at one end to a main chain and having projecting studs at the free ends, are transported by the main chain through a track having horizontal lengths and corners therein, said cars having car 15 cams at the free ends and positioning plates at the fixed ends, sprockets with which said chain engages at the corners of the tracks, intermediate sprockets driven by said chain sprockets and having notches which receive the studs at the 20 free ends of the cars, guides adjacent the corners with which the cams at the free ends of the cars engage to direct the free ends of the cars
- toward the intermediate sprockets, and holding guides fixed adjacent the track at the corners and having projecting fingers, the positioning plates on the cars normally pass freely over the first mentioned guides and behind the fingers of the second mentioned guides, said fingers in case the cars tip engaging the positioning plates and preventing them from contacting with the first mentioned guides.
9. A conveyer system comprising an endless 10 main chain having horizontal runs, an upward run and a downward run, a plurality of cars fixed to said chains at predetermined intervals, mechanism for engaging and maintaining the cars horizontal while turning the corners, and 15 a plurality of auxiliary chains one adjacent the upward run and the other adjacent the downward run for engaging the cars and maintaining them horizontal during their upward and downward travel.

CHESTER S. JENNINGS.

20
